UNITED STATES PATENT OFFICE.

HERBERT S. JONES, OF BETHLEHEM, PENNSYLVANIA.

ELECTRIFIED SATCHEL.

1,288,909.

Specification of Letters Patent. Patented Dec. 24, 1918.

Application filed December 29, 1917. Serial No. 209,474.

To all whom it may concern:

Be it known that I, HERBERT S. JONES, a citizen of the United States of America, residing at Bethlehem, in the county of 5 Northampton and State of Pennsylvania, have invented new and useful Improvements in Electrified Satchels, of which the following is a specification.

The invention relates to a protective 10 means to be applied to satchels, valises, suit cases and the like and its principal object is the provision of unique means for electrifying a satchel, so that, should it be picked up by a person other than the owner, 15 such person will receive a shock.

Another object of the invention is the provision of a unique switching arrangement by which the electric circuit may be rendered operative or inoperative.

20 Still another object is the provision of a floating connection, whereby intermittent shocks will be imposed on the hand which carries the satchel when the latter is vibrated, as is usually the case when a satchel 25 is being carried.

Still another object is to provide a neat and effective way of producing the electric shock and to provide also an inexpensive device of this kind for attachment to the 30 ordinary satchel or valise.

Other and further objects will appear as the detail description of the device progresses.

While the invention is illustrated in but 35 one embodiment, it is to be understood that other embodiments are possible without departing from the spirit of the appended claims, or sacrificing any of the advantages of the invention.

40 Throughout the drawings, the same numerals of reference designate the same parts in all of the several figures, wherein:

Figure 1 is a perspective view of a satchel embodying the invention.

45 Fig. 2 is a longitudinal sectional view. Referring to the drawings, there is shown a conventional form of satchel 1 which opens on the upper longitudinal edge in the usual way. The pivotally connected closure members 2 of the satchel are of the usual 50 form and are made preferably of metal and to these the leather or fabric portions of the satchel is attached.

One of the closure members 2 of the 55 satchel carries two metal eyes 3 and 4, the eye 4 being attached to the member 2 in the

usual way but the eye 3 being attached thereto in such a manner as to be electrically insulated therefrom, this insulation being indicated by the numeral 5 in Fig. 2. 60

The handle 6 is of the conventional form and carries electric conducting wires 8 65 enclosed within it, each of these wires connecting with one of the rings 7 at one end and at the other end each connects with an L-shaped plate 9 set in the handle to project out to the underface thereof where both plates lie flush with the underface of the handle and are in close proximity to each other but not in contact. The handle 6 is 70 intended to be made of a material usually used for such handles, so that the handle in itself may be a non-conductor.

On the upper edge of that closure member 2 to which the eyes 3 and 4 are connected, 75 there is a slidably mounted stud 10 adapted to move in the slot 11 formed in the closure member in the direction of its length. That portion of the stud 10 which engages the slot is of smaller diameter than the head 80 thereof and the smaller portion projects into the interior of the satchel where it receives a small collar 12, thus permitting the stud itself to move longitudinally in the slot but preventing it from vertical movement 85 therein.

On the under face of the closure member 2, there is a contact member 13 which is pivoted at its longitudinal center on a support 14, the latter being held on the underface of the closure member 2 but suitably insulated therefrom by an insulating strip 15. The contact member 13 is so designed that it hangs substantially in a horizontal position when the body 1 is raised in a 90 horizontal position but the extreme end 16 inclines downwardly from this horizontal plane. When the switch stud 10 is moved to that end of the slot adjacent to which the contact member is hung, the lower end 100 of this stud 10 is in close proximity to the depending ends 16 and any vibration imparted to the contact member 13 will result in bringing the stud 10 and the depending end 16 into contact for a purpose yet to be 105 described.

A suitable pocket 17 is formed on the interior of the satchel and this pocket carries a battery 18 and a shock coil 19. One terminal of the battery is connected to the 110 closure member 2 by a wire 20 while the other terminal thereof is connected to one

terminal of the shock coil by a wire 21. The other terminal of the shock coil connects with the contact member 13 and with the eye 3 by wires 22 and 23 respectively.

5 For the purpose of illustration, let it be assumed that the stud 10 has been moved over to that end of the slot 11 where it may be contacted with by the contact member 13 and let it be assumed that the contact member 13 is in contact with the stud. The battery 18 will then supply current through the wire 20 to the closure member 2 which current flows into the stud, 10, thence to the contact member 13, thence to the shock coil 19 by means of the wire 22 and thence back to the battery 18 by means of the wire 21. Presume the contact member 13 after this to be separated from the stud 10 such as would result from shaking the satchel or 20 from any other operation that would cause the contact member to vibrate on its pivotal connection. The self-inductance of the shock coil 19 will then set up a counter-current in the coil and if anything be across 25 the contact plates 9, such as a hand, this current will flow through the wire 21, through the battery, through the wire 20, on to the closure member 2, the eye 4, one ring 7, one wire 8, the plate 9, through the connection 30 presumed to be between the two plates, on to the second plate 9, through the second wire 8, on to the second ring 7, on to the eye 3, and thence back to the shock coil through the wire 23. If a hand be across 35 the two contact plates 9, such as would be the case were anybody to undertake to lift the satchel this induced current in the shock coil would impart a very preceptible shock to the hand and whosoever had lifted the 40 satchel could not but fail to give evidences of such a shock. The pivotally mounted contact member 13 provides a means for intermittently closing the circuit of the battery and the shock coil in case the grip is raised, for this pivotally mounted contact member will be thrown into vibration by 45 raising the grip. This intermittent opening and closing of the battery circuit re-

sults in the self-inductance of the shock coil causing a current to flow through the circuit 50 just described and to impart a shock to any sensitive object, such as a hand, that may be in contact with the two plates 9.

The satchel is provided with the usual lock member attached to the closure member 2 and the switch stud 11 is intended to match this locking member in appearance. The object of making the locking member 24 and the stud 10 identical in appearance is to enable the owner of the 60 satchel equipped with this arrangement to shift the shocking device into circuit on the pretense of locking the satchel, thus it will not be made apparent to lookers-on that a trap is being set for whomever may attempt to purloin the satchel.

The invention having been described, what is claimed as new and useful is:

1. In a device as set forth, the combination with a satchel having a handle, of a 70 primary electric circuit carried within the satchel, a floating connection in said primary circuit, and a secondary circuit derived from the primary circuit, said secondary circuit extending into the handle where- 75 by a shock may be imparted to the hand that undertakes to lift the satchel.

2. In a device as set forth, the combination with a satchel having a handle, of a 80 slidably mounted stud carried by one closure member of the satchel, a floating contact member insulated from and carried on the underface of said closure member, a pocket within the satchel, a battery, and a shock coil carried within the pocket, the 85 battery and the shock coil being electrically connected together and to the closure member and to the contact member respectively, electrical connections carried within the handle, and plates also carried in the handle 90 and in spaced relation and in close proximity to each other, the aforesaid electrical connections connecting with the battery and with the shock coil respectively.

In testimony whereof I affix my signature. 95
HERBERT S. JONES.
